UNITED STATES PATENT OFFICE

ALBIN H. WARTH, OF BALTIMORE, MARYLAND, ASSIGNOR TO CROWN CORK & SEAL COMPANY, INC., OF NEW YORK, N. Y., A CORPORATION OF NEW YORK

BOTTLE CLOSURE

Application filed April 4, 1930. Serial No. 441,461.

My invention relates to bottle closures, and more particularly to bottle closures of the type embodying therein a sealing disk carried by a skirted metallic shell.

5 Heretofore, it has been a common practice to produce bottle closures consisting of a metal shell having a fluted skirt, the inner face of the top of which shell had cemented thereto, a cushion disk which, in some instances, was made of natural cork, and in other instances, of composition cork, formed of cork granules united by a suitable binder.

10 In order to prevent oxidation of the exposed surface of the disk, discoloration therefrom of the contents of a bottle or other container, disintegration of the material of the disk when composition cork was used, and contamination of the contents of a bottle or other container as a result of bacteriological action, it has long been the practice to provide the exposed face of the cushion disk with a thin film of wax, or with what is known as a center spot of specially treated paper, or of a metal foil.

15 While such caps have always given highly satisfactory results, the use of wax as a surfacing did not always meet the requirements of the bottler, particularly when the closures were used upon containers, the contents of which required sterilization, pasteurization or cooking after the closure had been applied thereto, since when subjected to high temperatures there was always the possibility that the wax surface might be disturbed.

20 Furthermore, there was also always the likelihood that tumbling the closures in the hopper of the bottle capping machine would disturb this coating. With some classes of beverages, including some spring waters, mineral waters whether natural or artificial, and foodstuffs having an acid content, the waxed cushions could not be used. To meet such conditions, center spot caps were produced, the material of the spot, however, varying 25 for use with different liquids or substances.

In the production of center spot caps, there have always been manufacturing difficulties, due to the necessity of reasonable accuracy in the location of the centers, so as to expose a 30 sufficient surface of the material of the cushion

ion about the center spot, to secure a proper sealing of the container. This was due largely to the tendency of the disk of the center spot moving in relation to the center of the cushion disk when pressure was applied thereto in cementing same in position, resulting from the viscosity of the cement used and the non-absorptive properties of the cushion disk.

35 I have recently developed a center spot cap wherein the bonding agent between the center disk and the cushion disk consists of gutta-percha tissue which has been found to adhere satisfactorily to an untreated surface of the cork, whether natural or composition, and to very materially reduce the wastage resulting from the center spot disks being off-center in relation to the cushion disk.

40 It is desirable, even when center spots are used, that the exposed surface of the cushion disk shall be treated or receive a thin coating 45 of a material having the characteristics of the wax above referred to, but the presence of such wax precludes the use of the center spot caps in the bottling of beverages or 50 foodstuffs with which the ordinary waxed surfaced cushion disk caps could not be used. Furthermore, the wax coating upon disks was restricted to the exposed surface 55 thereof, and when center spots were used, it was necessary to apply the wax after the application of the disk.

55 The above condition was due to the fact that the cushion disk must be cemented to the shell to permit the handling of the caps 60 in the capping machine, and the center spots must be cemented to the face of the disk so that the presence of wax throughout the areas where the use of cement was required prevented a proper bonding action.

65 With the above conditions in mind, I have provided a bottle closure or other container cap employing a cushion disk of natural or composition cork, wherein the exposed surface of the cushion disk is provided with a 70 thin, transparent coating of non-absorbent, acid resisting, infusible and non-oxidizing material having sufficient inherent resiliency and elasticity to readily conform to any distortion of the cushion disk during the application.

cation of the closure to a container. This coating will also serve, as did the wax coating, to fill minute surface imperfections or voids in the cushion disk.

- 5 In addition to the characteristics above referred to, the surface coating may be applied throughout the entire surface of the cushion disk and permit the more effective utilization of gutta-percha tissue as a binding material 10 in affixing a center spot to the cushion disk, since the rapid coalescence of the fused gutta-percha with this surface coating avoids that slippage which results in the accidental locating of such spots off-center.
- 15 The invention consists primarily in a bottle closure embodying therein a metal shell, and a cushion disk formed of cork provided with a thin transparent coating of non-absorbent, acid resisting, infusible, non-oxidizing 20 material having inherent resiliency and elasticity; and in such other novel characteristics as are hereinafter set forth and described, and more particularly pointed out in the claims hereto appended.
- 25 Referring to the drawing,

Fig. 1 is a bottom plan view of a center spot disk closure embodying the invention; and

30 Fig. 2 is a cross section thereof.

Like letters refer to like parts in both of said views.

In the accompanying drawing, I have shown the invention as applied to a bottle closure of the crown type, embodying therein 35 a shell of the usual formation, the top of which is shown at *a*, and the fluted, outwardly flared skirt of which is shown at *b*, the drawing being upon a much enlarged scale.

Within the metal shell is shown a cushion 40 disk *c* which consists of composition cork. The metal shell is provided with the usual inner coating of lacquer, and the cushion *c* is cemented thereto in the usual manner. The entire surface of the cushion disk *c* is 45 provided with a thin coating, a mere film, of an unvulcanized rubber compound, having a low content of vulcanizing medium and a water soluble, accelerator, but no filler, so that when subjected to a low temperature, or 50 to warm air, it will develop the properties of being non-absorbent, acid resisting, infusible and non-oxidizing while possessing sufficient inherent resiliency and elasticity to readily conform to any distortion of the disk *b* when 55 subjected to pressure while being applied by a capping machine. Preferably, I use water dispersed rubber in the compound, which is indicated at *d*.

60 It is desirable to apply the coating *d* to only one surface of the disk *c* as by so doing manufacturing difficulties are reduced to a minimum, and the necessity for the use of the coating is such as not to require its application to any other portion of the cushion disk.

65 A closure having the exposed surface of the

cushion disk coated, as above described, not only possesses characteristics which will prevent the discoloration of the exposed face of the cushion disk and the deleterious action of the contents of the bottle upon the disk, or 70 of the disk upon the contents of the bottle, but ensures a more effective sealing of a bottle as a result of the closure of minute openings in the surface of the cushion disk, and the conformation of the surface coating to the 75 disk when distorted by the application of pressure when applying the closure to a bottle or other container. This coating, however, will also greatly facilitate the application of a center spot, such as *e*, to the cushion 80 disk, particularly when fusible adhesive, such as gutta-percha tissue indicated at *f*, is employed for binding such center spot disk to the cushion disk. The gum of the surface coating and the gum of the tissue, upon the application of heat throughout the area of the disk *e*, will both become more or less tacky and thus not only expedite the binding action, 85 as the material of the coating and the tissue set upon cooling, but avoid any material side slipping of the center spot disk because the coating is already bonded to the cork.

90 I have found, in actual practice, that it is desirable to produce the coated disks by applying a solution of water dispersed rubber 95 compound as described, to a sheet of cork or composition cork, and cutting disks therefrom after the solution has become thoroughly dry. While, during the cutting operation, the drag of the dies may remove small portions of the coating about the edge of the disks, this is immaterial so far as the efficiency of a disk so coated is concerned. I consider this procedure preferable to attempting to coat previously formed disks by 100 immersion, or other methods, although this procedure might be followed. A thinner and more uniform coating, however, can be secured in the manner I have above described.

105 The center spot disk *e* may be formed of specially treated paper, tin foil, aluminum foil, or zinc foil, according to the character of the beverage or foodstuff with which the closures are to be used.

110 For some uses, this center spot disk *e* may be entirely dispensed with, particularly when it is desired to reduce the cost of production of the closures.

115 It is not my intention to limit the invention to the precise details of construction of the closure herein set forth, nor to the manufacturing methods described, since it is obvious that such may be varied without departing from the spirit and scope of the invention.

120 I believe it to be broadly new, however, to provide a closure having a transparent coating of pure, semi-vulcanized rubber, or a material having similar properties, upon the 125 surface thereof exposed within a closure, and I intend to claim such broadly.

Having described the invention, what I claim as new and desire to have protected by Letters Patent, is:—

1. A bottle closure embodying therein a metal shell, and a cushion disk formed of cork provided with a thin transparent coating of non-absorbent, acid resisting, infusible, non-oxidizing material having inherent resiliency and elasticity.
- 10 2. A bottle closure embodying therein a metal shell, and a cushion disk formed of cork provided with a thin surface coating consisting of a film of semi-vulcanized rubber.
- 15 3. A bottle closure embodying therein a metal shell, and a cushion disk formed of cork provided with a thin coating of semi-vulcanized water dispersed rubber.
- 20 4. A bottle closure embodying therein a metal shell, and a cushion disk formed of cork provided upon the exposed surface thereof only with a thin surface coating consisting of a film of semi-vulcanized rubber.
- 25 5. A bottle closure embodying therein a metal shell, a cushion disk formed of cork provided with a thin transparent coating of non-absorbent, acid resisting, infusible, non-oxidizing material having inherent resiliency and elasticity, a center spot, and an adhesive having an affinity for said coating material between said spot and the surface coating of the disk.
- 30 6. A bottle closure embodying therein a metal shell, a cushion disk formed of cork provided with a thin coating of semi-vulcanized rubber, a center spot, and a stratum of gutta-percha between said spot and the rubber coating.
- 35 7. A bottle closure embodying therein a metal shell, a cushion disk formed of cork provided with a thin coating of semi-vulcanized water dispersed rubber, a center spot, and a stratum of gutta-percha between said spot and the rubber coating.
- 40 8. A bottle closure embodying therein a metal shell, a cushion disk formed of cork provided upon the exposed surface thereof only with a thin coating of semi-vulcanized rubber, a center spot, and a stratum of gutta-percha between said spot and the rubber coating.
- 45 9. A bottle closure embodying therein a metal shell, a cushion disk formed of cork provided upon the exposed surface thereof only with a thin coating of semi-vulcanized rubber, a center spot, and a stratum of gutta-percha between said spot and the rubber coating.

In witness whereof I have hereunto affixed my signature, this 31st day of March, 1930.

ALBIN H. WARTH.
